(57) CLAIM

I claim the ornamental design for a tent, as shown and described.

DESCRIPTION

FIG. 1 is a top front left perspective view of a tent;

FIG. 2 is a rear elevational view thereof;

FIG. 3 is a front elevational view thereof;

FIG. 4 is a left side elevational view thereof;

FIG. 5 is a right side elevational view thereof; and,

FIG. 6 is a top plan view thereof.

The broken lines shown in the drawings depict portions of the tent that form no part of the claimed design.
